UNITED STATES PATENT OFFICE.

LOUIS H. PERLMAN, OF NEW YORK, N. Y.

WHEEL.

1,261,605.

Specification of Letters Patent.

Patented Apr. 2, 1918.

Application filed September 23, 1916. Serial No. 121,828.

To all whom it may concern:

Be it known that I, LOUIS H. PERLMAN, a citizen of the United States, residing at New York city, in the county of New York 5 and State of New York, have invented certain new and useful Improvements in Wheels; and I do hereby declare the following to be a full, clear, and exact description of the invention, such as will enable 10 others skilled in the art to which it appertains to make and use the same.

This invention relates to improvements in demountable rims, and more particularly to the channel type of the class known as cross 15 cut.

The object in view is the provision of simple and efficient means for the locking of the ends of the rim together.

With this and other detail objects in 20 view, the invention comprises certain novel constructions, combinations and arrangements of parts as will be hereinafter specified and claimed.

In the accompanying drawing,—

25 Figure 1 is an inverted plan view of a rim embodying the features of the present invention.

Fig. 1^a is a detail perspective view of the locking key detached.

30 Fig. 2 is a section taken on the plane indicated by line 2—2 of Fig. 1, a fragment of a wheel body being seen.

Fig. 3 is a vertical section taken on the plane indicated by the line 3—3 of Fig. 1.

35 Fig. 4 is a view similar to Fig. 1 of a different embodiment of the invention.

Fig. 5 is a similar view of a further embodiment.

40 Fig. 5^a is a view similar to Fig. 1^a of the key seen in the structure disclosed in Fig. 5.

Fig. 6 is a perspective view of a modified form of locking key.

Referring to the drawing by numerals, 1 indicates a wheel body provided with the 45 usual fixed rim or felly band 2, which has at its inner end the outwardly flaring stop flange 3. Removably surrounding the felly band 2 is the demountable rim 4, which is of the channel type, having side flanges for

50 retaining the non-extensible marginal beads of a pneumatic tire. The inner edge of the

rim 4 rests against and is supported by the flange 3, while the outer edge is sustained by the usual locking wedges, or other similar locking devices, not illustrated.

55

The rim 4 is cross cut forming end portions 5 and 6. To the under face of the end portion 6 is fixed a plate or strap 7 which extends across the cut and underlies the end portion 5. Plate 7 is shown as riveted to the end portion 6, but, obviously, it may be otherwise fixed thereto as preferred. The free end portion of the plate 7 is stamped or otherwise appropriately shaped to form a hook 9 arranged crosswise of the rim and formed to provide a key-receiving recess. In other words, the offset formed by hook 9 is arranged with its longitudinal axis parallel to the axis of the wheel on which the rim is mounted. At each end of hook 9 the end portion 5 is formed with an eye 10, the eyes 10 being alined with the hook 9 when the parts are in operative position. A key 11 extends through the eyes 10 and hook 9 and serves to lock the parts together, thus locking the ends 6 and 5 against relative movement. It should be noted particularly from Fig. 2 that the hook 9 is flat so as to occupy a minimum amount of space between the demountable rim and the felly band. Also, 70 as a matter of economy of space, the hook 9, while serving as a key-receiving eye, is in fact formed with its inner side and two edges constructed of the material of plate 7, while the outer side is closed by the material of the base of the demountable rim; that is to say, the plate 7 is merely stamped with an offset providing a rectangular recess which becomes an eye when the plate is in contact with the end portion 5. The plate 75 cannot leave this position when the rim is in operation because the under face of the material of plate 7 forming the eye is sufficiently contiguous to the felly band to prevent appreciable radial inward movement of 80 the plate. The eyes 10 may be constructed in various ways, but, as a matter of economy in material and weight, the eyes 10 are 85 preferably stamped directly from the material of the base of the rim 4, as clearly indicated in Fig. 3.

75

The key 11 is flat and rectangular corre-

100

sponding to the shape of the openings in the eyes 10 and hook 9, and is provided at its inner end with a head 12, and by "inner end" is meant the end toward the inner side 5 of the demountable rim, that is, toward the flange 3.

The operation of the structure is simple and readily understood and may be briefly set forth as follows: The rim is mounted 10 and demounted in the usual manner of any ordinary demountable rim. When it is desired to interchange tires on the rim, the key 11 is withdrawn and the end portion 6 is depressed until the flanges of that end portion free themselves from the end portion 5 and then the end portion 6 is either 15 swung axially and the rim and tire are separated with a movement similar to the unthreading of an external thread from an internal thread, or else the end portion 6 is further depressed and caused to move to a position sufficiently lapping the end portion 5 to effect the necessary contraction in the effective diameter of the rim to enable the 20 rim to be withdrawn from the tire or the tire from the rim. To apply a new tire the converse operation is carried out.

It is to be noted that the head 12 being presented toward the flange 3 will effectively 25 prevent loss of the key 11 during operation of the rim, but when the rim is carried as a spare it is preferable to assure retention of the key by the use of a cotter pin (not shown) passed through an aperture 13 formed in the outer end of the key 11.

In Fig. 4 is illustrated the same structure as above described, except that eyes 10' are employed in lieu of the eyes 10, the eyes 10' being formed of separate plates of material 40 riveted to the end portion of the rim instead of being stamped directly from the material thereof. As the other parts are identical, the same reference numerals have been applied and the same description applies.

In Fig. 5 is illustrated a further embodiment in which the structure is identical with that above described except the eyes 10'' and the hook 9'' are formed tapering in the direction of their length with a uniform taper 50 throughout the series of eyes so as to receive a tapered key 11''. The structure and function of all of the other parts being the same, the same reference numerals have been applied and the same description 55 will apply. It is obvious, of course, that the taper of the key 11 is to enable loosening of the key radially in the event of the key becoming tight during use.

As a further means of insuring ready loosening of the key, there is illustrated in Fig. 6 a further modified form of key 11^a of the form of an ellipse in cross section. The eyes and hook employed with the key 11^a

would, of course, be shaped to correspond with the shape of the key.

It has heretofore been proposed to connect the ends of a cross-cut demountable rim by leaves or plates fixed to the respective ends of the rim and formed with eyes adapted to register when the ends of the rim are in operative relation. All of those forms proposed, however, with which I am familiar, have included eyes whose openings are circular in cross section so that the locking key or pintle has been in each instance in the 75 form of a cylinder. These proposed devices have not been successful because the space which may be allotted in a practical wheel structure for such locking devices is not sufficient to enable the use of a cylindrical 80 pintle and a circular eye of sufficient dimensions to resist the expanding and other stresses to which the modern demountable rims are subjected both from the action of the locking wedges and from the distribution of load and shock strains. The present invention overcomes the difficulties thus presented by avoiding the need for increased space between the demountable rim and felly band, and at the same time providing 85 (through any additional width that may be found required) all the necessary metal to carry the strains.

What I claim is:—

1. In a wheel structure, a demountable rim 95 of the channel type having a cross cut, a plate connected with one end portion of the rim and extending across the cross cut and formed with a transverse recess, eyes on the other end portion of the rim registering 100 with the recess, and a key flat in cross section extending through and snugly fitting the recess and eyes for connecting the rim ends against separation under expanding stresses.

2. In a wheel structure, a demountable rim of the channel type having a cross cut, a plate connected with one end portion of the rim and extending across the cross cut and formed with a substantially flat hook, eyes 110 on the other end portion of the rim registering with the hook, and a key extending through and connecting the hook and eyes.

3. In a wheel structure, a demountable rim of the channel type having a cross cut, a 115 plate connected with one end portion of the rim and extending across the cross cut and formed with a substantially flat hook, eyes on the other end portion of the rim registering with the recess of the hook, and a key 120 also substantially flat in cross section extending through and connecting the hook and eyes, the eyes being stamped from the material of the rim.

4. In a wheel structure, a demountable rim 125 of the channel type having a cross cut, a

plate connected with one end portion of the rim and extending across the cross cut and formed with a substantially flat hook, eyes on the other end portion of the rim register 5 with the hook, and a key also flat in cross section extending through and connecting the hook and eyes.

In testimony whereof I affix my signature in presence of two witnesses.

LOUIS H. PERLMAN.
